UNITED STATES PATENT OFFICE.

JOSEPH HAAG, OF PARIS, FRANCE.

FASTENING DEVICE FOR THE DOORS OF RAILWAY WAGONS AND OTHER VEHICLES.

Application filed August 25, 1921. Serial No. 495,173.

(GRANTED UNDER THE PROVISIONS OF THE ACT OF MARCH 3, 1921, 41 STAT. L., 1313.)

To all whom it may concern:

Be it known that I, JOSEPH HAAG, a citizen of the Republic of France and residing at Paris, Seine Department, No. 19 Rue Constance, in the Republic of France, engineer, have invented certain new and useful Improvements in Fastening Devices for the Doors of Railway Wagons and Other Vehicles (for which I have filed an application in France, November 5, 1913, Patent No. 464,471), of which the following is a specification.

My invention relates to improvements in fastening devices for the doors of railway wagons or other vehicles, of the type where-in the lock comprises an inner knob or handle adapted to slide and to rotate, and two bolts whereof one is actuated by the sliding movement of the inner handle and the other by the rotation of the said handle. The said improvements have for their object to afford a very simple construction for a fastening device of this character and to render the said device very easily mounted upon doors, these latter being cut in to only a slight degree and in a very simple shape.

For this purpose, the inner handle draws with it in the vertical movements thereof a sliding member which drives back one of the bolts through the intermediary of a bell-crank lever or more directly by means of an inclined plane. The said handle is also provided with a finger engaging a suitable projection of the second bolt whereby the latter shall be actuated upon turning the said handle. The two bolts are actuated at the same time by means of the outer handle, one of the said bolts being controlled directly by a finger secured to the said handle, the second bolt being controlled by a projection of the first bolt. This mechanism which is of a very simple character is mounted in a flat rectangular casing which is inclosed on the four sides by partitions. To mount the said casing upon the door, it will suffice to form a corresponding rectangular cut out portion therein which has but a slight depth, thus requiring a minimum amount of labor and without weakening the said door.

The following description, together with the accompanying drawings, sets forth three embodiments of my invention.

Fig. 1 is a side elevation of the first embodiment.

Fig. 2 is a front elevation of the same, viewed from the interior.

Fig. 3 is a side elevational view showing the bolts drawn in, the partitions of the lock being removed.

Fig. 4 is a longitudinal section on the line A—A Fig. 2.

Fig. 5 is a diagrammatic view of the mechanism of the second embodiment, the closing springs and the operating device by the outer handle being removed.

Fig. 6 shows a third embodiment, with the bolts in the closing position, and

Fig. 7 a like view with the first bolt opened.

Fig. 8 is a section on the line A—A Fig. 6.

Fig. 9 is an elevational view of the inner handle of the preceding lock, and

Fig. 10 is a cross-section of the said handle.

1 and 2 indicate two bolts of the said lock which are guided within suitable cut out portions of a frame 3 secured to the main plate of the lock, 4, the said frame constituting partitions upon the four sides 80 of the latter. One end of the said main plate is bent up to form a cross-member 5, and the frame 3 is provided with a corresponding lug 6 which is secured to the said cross-member. On the opposite side, the 85 said frame has a cut out portion 7 for lightening the same. Across the said bolts is disposed a sliding member 8 having pivoted thereto the inner door handle 9 whose shank 10 extends through a vertical-groove 11 in 90 the main plate. The said sliding member is vertically guided at the bottom by a cut out portion of the frame 3 and at the top by the groove 11. It is provided at the lower part with a projection 12 adapted to 95 engage one arm of a bell-crank lever 13 pivoted at 14 upon the main plate, the other arm of the said lever entering in contact with a shoulder 15 of the bolt 1 in such manner as to impel the said bolt inwardly 100 against the action of the spring 16.

To the shank 10 of the inner door handle is secured a finger 17 engaging the shoulder 18 of the bolt 2 whereby the latter shall be impelled against the action of the spring 19. 105 When the sliding member is lowered, Fig. 2, the finger 17 is now engaged between the stop pieces 20, 21 secured to the main plate and is thereby prevented from swinging to the right or left. In the main plate and in 110

a lug of the said frame is journalled the hub 22 of a striker 23 adapted to impel the bolt 2 inwardly by acting upon the shoulder thereof 24. The hub 22 is provided with a 5 square aperture adapted to receive the shank of the outer door handle, not shown. When the bolt 2 is thus driven back, it drawn along the bolt 1 by means of a finger 25 secured to the first bolt and engaging a finger 10 26 secured to the second bolt. When the door is closed, the said sliding member is lowered and the door handle 9 is thereby prevented from turning, the finger 17 being held firmly between the members 20, 21. 15 The lock may now be opened from the exterior in the usual manner, the bolt 2 being drawn inwardly by the striker 23 and the bolt 1 being also drawn inwardly by the bolt 2 and the fingers 25, 26.

20 To open the lock from the interior, it is required to raise the handle 9 in first place and to then turn the same. The first movement has the effect of lifting the sliding member 8 in such manner that the projection thereof 12 shall cause the lever 13 to swing, this latter impelling the bolt 1 inwardly. The second movement effects the rotation of the finger 17 which is now disengaged from the members 20, 21 and impels 25 the bolt 2 inwardly. Upon releasing the door handle 9, the springs 16, 19 cause the bolts to return outwardly, whereupon the lever 13 is returned to the inoperative position and obliges the sliding member to descend, whereas the finger 17 is caused to assume the upright position and is brought back between the stop pieces 20, 21.

The form of construction which is shown diagrammatically in Fig. 5 differs from the 40 preceding form by the fact that the lever 13 is suppressed, the projection 12 of the sliding member 8 and the shoulder 15 of the bolt 1 having the shape of inclined planes which are so formed that the lifting of the 45 said sliding member shall effect the backward movement of the said bolt and that the return movement of this latter bolt shall effect the lowering of the said sliding member. One of the inclined planes 12 or 15 50 may be replaced by a rounded surface or a roller.

In the form of construction shown in Figs. 6, 7 and 8, the sliding member 8 is ended at the level of the shank 10 of the 55 door handle, thereby affording a larger space for the finger 17 controlling the second bolt, and enabling the latter member to be given all the required strength. The lower part of the sliding member 8 is pro-

vided as in the preceding case with a projecting portion 12 engaging the bell-crank lever 13 in such manner as to effect the opening of the bolt 1, Fig. 7, upon raising the handle 9. The said handle is horizontally disposed, as shown in Fig. 8, and it 60 may therefore be very easily raised, and moreover, the passenger will instinctively execute this movement. To simplify the construction it comprises a plate 27 supporting the shank 10 provided with a recess 28 65 wherein the handle properly as called is maintained by a separate bracket 29 which is secured for instance by a screw 29^a. To facilitate the lifting movement of the said handle, the plate 27 is provided with a row 70 of balls 30 adapted to roll upon the surface of the main plate 4.

31 is a projection adapted to guide the finger 17 and 32 a projection adapted to guide the sliding member 8.

80

Claims:—

1. In a fastening device having two bolts, the combination of a vertical sliding member carrying the inner handle and a finger secured to the shank of the said handle, the 85 said sliding member being adapted to effect a longitudinal movement whereby one of the said bolts shall be drawn into the opening position, the said finger being adapted to act upon the other bolt in such manner as 90 to impel the same inwardly upon rotating the said handle.

2. In a fastening device having two bolts, the combination of a vertical sliding member carrying the inner handle, a finger secured to the shank of the said handle, a striker provided for the outer handle, and a frame constituting at the same time the walls of the said fastening-device, the 95 guides for the said bolts and for the said 100 sliding member, and one of the bearings of the striker of the outer handle.

3. In a fastening device having two bolts and comprising a vertical sliding member carrying the inner handle and a finger secured to the shank of the said handle, a plate constituting the base of the said handle and provided with balls whereby it is enabled to slide upon the main plate, whereupon the handle properly so called is maintained by a removable member.

In testimony, that I claim the foregoing as my invention I have signed my name in presence of a subscribing witness.

JOSEPH HAAG.
